I claim the ornamental design for a bottle, substantially as shown.

DESCRIPTION

FIG. 1 is a front isometric view of a first embodiment of a bottle.

FIG. 2 is a front elevation view of the bottle of FIG. 1.

FIG. 3 is a rear elevation view of the bottle of FIG. 1.

FIG. 4 is a left side elevation view of the bottle of FIG. 1.

FIG. 5 is a right side elevation view of the bottle of FIG. 1.

FIG. 6 is a top plan view of the bottle of FIG. 1.

FIG. 7 is a bottom plan view of the bottle of FIG. 1.

FIG. 8 is a front isometric view of a second embodiment of a bottle.

FIG. 9 is a front elevation view of the bottle of FIG. 8.

FIG. 10 is a rear elevation view of the bottle of FIG. 8.

FIG. 11 is a left side elevation view of the bottle of FIG. 8.

FIG. 12 is a right side elevation view of the bottle of FIG. 8.

FIG. 13 is a top plan view of the bottle of FIG. 8; and,

FIG. 14 is a bottom plan view of the bottle of FIG. 8.
